UNITED STATES PATENT OFFICE

JOHN ROYDEN PEIRCE, OF NEW YORK, N. Y., ASSIGNOR TO INTERNATIONAL BUSINESS MACHINES CORPORATION, OF NEW YORK, N. Y., A CORPORATION OF NEW YORK

PRINTING TABULATING MACHINE

Application filed December 27, 1924. Serial No. 758,359.

This invention relates to tabulating machines of the type wherein data are taken from perforated cards to control accumulating and printing operations of the machine. 5 The main object of the invention is to improve generally upon machines of this character; as for instance, by so constructing and arranging the parts and the mode of operation as to obtain greater operating speed 10 and a higher degree of reliability than is at present possible. It is also aimed to increase the usefulness of this class of machines by producing a machine capable of a greater range of results.

15 Another object is to provide means whereby any one or more of the type bars may be controlled to suppress printing thereby without suppressing accumulating operations of the corresponding accumulator wheels.

20 Another object is to provide a machine wherein the printing of a character in a particular column will control the printing of zeros to the right of such column and also to provide means whereby a split may be 25 effected at any point along the printing line beyond which such control shall not extend.

Another object is to provide means whereby when a type bar which carries the accumulated racks rises beyond the 9 position, 30 suppression of the carrying operation from the corresponding accumulator wheel to the wheel of the next higher order may be effected, so that the adding of 10 to any given accumulator wheel, besides placing such 35 wheel in the position which it occupied before, will also leave the wheel of the next higher order in its former position. Other objects will appear in the following description of the invention.

40 Referring to the drawings wherein the preferred form of the invention is shown:

Fig. 1, is a view of the assembled machine.

45 Fig. 2, is a plan view thereof.

Fig. 3, is a front sectional elevation taken on line 3—3 of Fig. 2, showing the card feeding and sensing mechanism.

50 Figs. 4 and 4^a, taken together comprise a section taken on line 4—4 of Fig. 2 showing

the hand operating levers for controlling the operations of the machine proper.

Figs. 5 and 5^a taken together comprise a section taken on line 5—5 of Fig. 2, showing cams and links controlled thereby for controlling the total taking operations of the machine.

55 Fig. 6 is the sectional elevation taken on line 6—6 of Fig. 2 showing the printing and accumulating mechanisms.

60 Figs. 6^a and 6^b are details of means for suppressing printing.

65 Fig. 7 is a front sectional view of the machine substantially on line 7—7 of Figs. 4 and 4^a showing the main drive, the main machine and the total cam groups and the mechanism connected thereto.

70 Figs. 8 and 9 are sections taken on lines 8—8 and 9—9 respectively of Fig. 7 showing the machine cams and followers.

75 Figs. 10 and 11 are front and rear views respectively of the accumulator unit, Fig. 10 being taken on line 10—10 of Fig. 6.

Fig. 12 is a section taken on line 12—12 of Fig. 10 of a portion of the accumulator 80 unit used in connection with group indicating.

Figs. 13 and 13^a are sections of the main portion of the accumulator unit taken on line 13—13 of Fig. 10 showing the parts in different positions.

85 Fig. 14 is an end view of the accumulator unit taken on line 14—14 of Fig. 10.

Fig. 15 is a detail of the accumulating and total-taking control mechanism.

Fig. 16 is a view of the cam actuated contacts and controlling the main machine and the total-taking operations.

Fig. 17 is a diagrammatic representation 90 of contacts used in connection with the group control features of the machine.

Fig. 17^a is a similar view of the total setting contacts.

Fig. 18 is a detail of the type bar position 95 controlling.

Fig. 19 is a detail of a restoring device for the mechanism showing in Fig. 18 taken on line 19—19 of Fig. 6.

100 Fig. 20 is a plan view of the mechanism

shown in Fig. 18 and is taken on line 20—20 of the latter figure.

Fig. 21 is a section taken on line 21—21 or Fig. 7 of a clutch for controlling the total-taking mechanism.

Fig. 22 is a perspective view showing the manner in which the data are sensed in the control card.

Fig. 22^a is a detail of the type rack showing its relationship to the paper supporting platen.

Fig. 23 is an electrical wiring diagram illustrating the manner in which the entire machine is controlled.

Fig. 24 is a section of the control box.

Fig. 25 is a section of said box taken on line 25—25 of Fig. 24.

Fig. 26 is another section of the control box, taken on line 26—26 of Fig. 24.

Fig. 27 is a diagrammatic representation of certain machine contact control cams in normal positions.

Fig. 28 is a similar view of total contact control cams.

Drive

The main drive of the machine comprises an electric motor 3 mounted on a bracket 4 attached to a cross member 5 fixed to the legs 2 of the machine. A belt 6 is connected between the motor and a pulley 7 on the main shaft 8. A worm wheel 9, Fig. 7, on the main drive shaft 10 is actuated by the worm 8^a. Fixed on said shaft 10 is a bevel gear 11 meshing with a bevel gear 12 on a shaft 13 which has fixed at its upper end a bevel pinion 14 (see also Fig. 6) meshing with a bevel gear 15 on a shaft 16. Fixed to the latter shaft is one element 17 of the card feed control clutch. The other element 18 is fixed on a shaft 19 which carries a gear 20 driving a chain of gears 21, 22 (Fig. 3), for operating the card feed rollers 23 and the card stacking member 24. A crank 25 pinned to one of the gears 21 is adapted to reciprocate card picker 26 on the guide rods 27. This picker, as is well known, is adapted to pick one card at a time from the stack 28 and feed it through the throat 29 to the first set of feed rollers 23, which feed rollers are resiliently pressed together by springs 30. The rollers will then carry the card to the stacker member 24 where it will be taken by the clips 31 and carried to an upright position in the stack 32 in the well known manner. As the card passes from the supply stack 28 to the receiving stack 32, it will pass under two sets of electric brushes 33 and 34. These brushes are adapted to engage contact elements 35, 36. While the card is passing between the brushes and said contact elements there will of course be no contact between the brushes and elements unless there is a hole in the card. A contact permitted by such a hole is adapted to control the printing and accumulating

operations of the machine as will hereinafter be described. Also as the card passes from one of the stacks to the other it is adapted to depress a member 37 and a similar member 38. These members are connected through rods 39 and 40 to contacts 41 and 41' in one case and contacts 42 in the other, so that when depressed such contacts will be closed, but when no card appears above the members 37, 38, such contacts will be permitted to open. The size of the throat 29 may be adjusted by actuating a screw 43 which is adapted to raise and lower the plate 44.

Machine control shaft

Aligned with the main drive shaft 10, Fig. 7, is the machine drive shaft 45, the latter is adapted to be driven by the former through a clutch 46 which clutch is in turn controlled by a magnet M. The shaft 45 carries a plurality of cams for actuating various parts of the machine in proper time relation to each other as will be pointed out.

Total shaft

Also aligned with the shaft 10 on the left-hand side of the machine is the total shaft 48, carrying a plurality of cams for actuating the total-set up mechanism. The shaft 48 is adapted to be clutched to the shaft 10 by a one revolution clutch controlled by a magnet T. The clutch, indicated generally at 49 in Fig. 7, is shown in greater detail in Fig. 21. A notched disc 51 shown in dotted lines forms one element of the clutch and is fast to the drive shaft 10 and rotates with it. Two members 55 and 57 are mounted on the shaft 48, the member 55 being fast on the shaft and the member 57 freely mounted thereon. Two pins, one of which is shown at 64^b project from the member 55 through perforations in the member 57, the diameter of the perforations being slightly larger than that of the pins. This permits a limited rotational movement between the members 55 and 57. On the pin at the right, as shown in Fig. 21, is pivoted a pawl 54 having a nose portion 53 adapted to cooperate with the notch 52 in the disc 51. This pawl is urged against the periphery of the disc 51 by a spring 58, one of whose ends is fastened to the pawl 54 and the other fastened to the member 55. A latch 63 pivoted at 66 to a lever 67, which in turn is pivoted at 68 to the frame 69 is urged by a suitable spring into position to engage a shoulder 61 on member 57. When the shoulder is thus engaged a pin 60 coacts with an extending tail 59 on the pawl 54 and rocks it clockwise against the action of spring 58 holding it away from the periphery of the disc 51. Incidentally the operation of the latch 63 owing to the pressure of pin 61 against tail piece 59 causes the members 55 and 57 to shift with respect to each other so

70

75

85

95

100

105

110

115

120

125

130

that pin 64^b moves against the lower surface of the perforation in the member 57. A spring pressed latching pawl 65 pivoted on latch 63 then engages a shoulder 64 on member 55 and locks the members firmly in their latched positions. The latch 63 below its pivot point 66 carries an armature 71 for the magnet T. Instantaneous energization of the magnet T attracts the armature 71 rocking the latch 63 clockwise about its pivot and releasing the shoulder 61 of the member 57. Spring 58 thereupon moves the pawl 54 against the periphery of the disc 51 whereupon at a given moment the nose 53 engages the notch 52 in the disc, clutching the shaft 48 to the shaft 10 and causing it to rotate therewith. When this occurs the tail piece 59 of pawl 54 presses against pin 60 and thereby shifts the members 55 and 57 with respect to each other to the relative positions shown in Fig. 21. At the end of half a revolution the latch 63, having now been released by the magnet T, engages a shoulder 61^a on the member 55 whereupon the pin 60 on member 57 presses against the tail piece 65 of the pawl 54 and rocks it out of engagement with the notch 52 causing the shaft 48 to come to rest after a half revolution. This operation will be repeated when the magnet T is again energized and the shaft 48 will rotate half a revolution at each release of the latch 63 upon energization of the magnet.

The machine shaft clutch 46, Fig. 7, heretofore referred to, is similar to the clutch shown in Fig. 21, excepting that the shoulders 61^a and 64^a are not provided so that the machine clutch instead of being a 180 degree clutch is a 360 degree clutch.

40 Operation of type bars

Referring now to Fig. 6, the type bars are shown at 73. Each bar carries at its upper end the type members 74, spring pressed by springs 75 as seen in Fig. 22^a to normal position out of contact with the platen 76. The type bars are carried in guide members 77, 78, and are normally held depressed by means of a restoring bar 79 engaging a projection 80 on the type bars. Springs 81 connected to 45 projections 82 on the lower end of the type bars and to brackets 83 carried on bar 79 tend to raise the type bars. Levers 84 fixed on each end of shaft 85 are connected through links 86 to the restoring bar 79. Shaft 85 extending across the machine has fixed on its outer end a lever 87 connected by a link 88, (see Figs. 7, 4 and 4^a) to a lever 89 fixed on stud 90. This stud as shown in Fig. 8 carries a bell crank lever 91 having cam followers 92, 93 cooperating with complementary cams 94, 95 fixed on the machine shaft 45. Thus while the machine shaft is rotating, the restoring bar 79 is raised and lowered once during each cycle of the shaft. As this 50 bar is raised the type bars 73 follow through the action of springs 81. At the same time it will be noted that these springs are being raised also by the restoring bar. If the type bars are stopped at an intermediate position while the restoring bar 79 continues to rise, 55 the springs 81 will, of course, stretch. On the lower end of each type bar is a ratchet member 96 adapted to cooperate with a stop ratchet 97 mounted in guides 98, 99. A spring 100 normally tends to move the stop 60 into cooperation with the member 96. The construction and operation of the stop latch 97 is shown in greater detail in Figs. 18 and 20. The rear end of the stop latch 97 is adapted to cooperate with a latching member 101 which is pivotally mounted at 102 and 103 in suitable supports 104. A spring 105 secured in the rear end of member 101 and to a fixed member 106 tends to draw the member 101 into cooperative engagement with the stop latch 97 to lock the latter in the position of Fig. 6 out of engagement with ratchet member 96. An electro-magnet 107 is adapted to act upon a projection 108 of the member 101, said member 108 comprising the armature of said magnet. Energization of this magnet will turn the member 101 against the action of its spring to release the stop latch 97 permitting it to engage the ratchet member 96. At this point it may be stated that while the card is being fed through the sensing portion of the machine shown in Fig. 3, the type racks are rising in synchronism so that while a given hole position of the card 109, Fig. 22, is passing under the brushes 34, the corresponding type element 74 will be passing, or, more specifically, reaching the printing line in Fig. 6. The closure of an electric circuit through the hole in the card will at this point cause energization of the electro-magnet 107 to release the stop latch 97 to stop the type bar in position to print the proper character. In order that the type bars 73 shall not be permitted to move to their upper limits when the stop latches 97 are 100 withdrawn, means such as a pawl 110, Fig. 6, cooperating with the ratchet teeth 111 on the type rack may be provided. A spring 112 tends to move the pawl into engagement with the ratchet teeth. A restoring plate 113 fixed 105 to levers 114, pivoted on opposite sides of the machine at 115, is provided to withdraw the pawls 110 from engagement with the type bars. Levers 114 have pin and slot connection with levers 116 fixed on shaft 117. Shaft 117 in turn is provided with a lever 118, Fig. 4, connected by a link 119, (see also Fig. 4^a) to a lever 120, fixed on a shaft 121 reaching into the machine cam box 122, Figs. 7 and 9, and having a cam follower lever 123 cooperating 110 with the cam 124. Spring 119^a holds the follower against the cam 124. At the proper time in the operation of the machine, i. e., after the type bars have all risen to printing 115 positions, the cam 124 releases the pawls 110, 120

to cooperate with the type bars. After printing and the type bars have been restored to their normal positions, having been clicked downwardly over the pawls 110, the cam 124 then moves the pawls from the type bars so that the latter are again free to rise during the next cycle of operation of the machine. After the type bars have all risen to printing position, the stop latches 97 are withdrawn by means of a bail 125, Figs. 6 and 18, fixed on a shaft 126. (See also Fig. 4.) A lever 127 also fixed on said shaft is connected by a link 128 to a lever 129, Fig. 4^a, fixed on a shaft 130. The shaft 130 carries a lever 131 having a cam follower 132 cooperating with the cam 133. Spring 128^a holds the follower against the cam. This cam is timed to turn the shaft 126, Figs. 18 and 6, after the type bars have reached their printing positions as we have seen, to restore the stop latches 97. These latches will then be engaged by members 101 as will be clear in Fig. 20. The magnets 107 at this time are, of course, not energized so that spring 105 will cause member 101 to latch the stop 97. In order to overcome residual magnetism which might otherwise tend to cause a lagging operation of springs 105, positive means may also be provided to move the members 101 into locking engagement with the stops 97. This means may comprise bars 134 having notches 135, cooperating with the members 101, the notches being wide enough to permit the normal operation of the members 101. These bars are secured at one end to a member 136. A bell crank lever 137 pivoted at 138 to the frame 139 has a pin and slot connection at 140 with the bars 134 and is connected by a link 141 (see also Figs. 4 and 4^a) to a lever 142 fixed on a shaft 143. As seen in Fig. 8 this shaft has fixed thereon a cam lever 144 having a limit projection 145 adapted to cooperate with shaft 90. Spring 141^a normally holds the parts in this position. The lower end of the cam lever is adapted to be engaged by a cam roller 146 carried by the cam 647. During each cycle of operation of the machine after the latch members 101 have been released by the magnet, the cam operates to actuate the bars 134 to the left as viewed in Fig. 19 to positively insure the restoration of such members to normal position. In two instances the slots 135 are wider than in the other instances so that the members 101^a and 101^b shall not be positively restored. In these cases spring pressed members 147 will engage the latch members 101^a and 101^b to add resilient force thereto so that when the respective magnets are de-energized, this additional force will serve to restore the latch members. The members 101^a and 101^b will be more fully described later.

Hammer control

65 In Fig. 6 the hammers for actuating the

type members 74 are shown at 148 loosely mounted on a shaft 149 and pressed by springs 150, connected at one end to said hammers and at the other end to the fixed plate 151, into printing action. The hammers are normally locked against such action by latches 152 engaging the lower projection 153 of the hammers. The latches 152 are loosely mounted on the shaft 154 and are pivotally mounted at their lower ends to the lever 155. A spring 156 normally holds each latch in operative position. The shoulder 157 on lever 155 is adapted when depressed to cooperate with a bail 158 fixed on a shaft 159. This shaft as seen in Fig. 4 has fixed thereto a lever 160 having pin and slot connection with the lever 161 on shaft 162. Also fixed on the latter shaft is a lever 163 connected by a link 164 (see also Fig. 4^a) to a lever 165 fixed on shaft 166. The latter shaft has fixed thereon a cam lever 167, Fig. 9, having a limit projection 168 cooperating with the shaft 169. The lower end of said cam lever is adapted to be struck by a roller 170 carried by a cam 171. A spring 164^a normally holds link 164 in its upper position. Actuation of the parts by the cam roller 170 causes clockwise rotation of shaft 159 to move the bail 158 to the left so that if the shoulders 157 are in cooperation with such bail the levers 155 will be moved to the left as viewed in Fig. 6 to unlatch the hammers whereupon the latter will be actuated by their springs to impel the type for printing. A pin 172 carried by each type bar 73 normally engages one end of lever 155 and holds the shoulder 157 out of cooperation with the bail 158. Should a type bar 73 rise beyond the zero printing position, the pin 172 releases lever 155 sufficiently to permit the same to cooperate with the bail 158 so that the corresponding hammers will be released when the bail operates. Should the type bar rise only to the zero position, however, the pin 172 will not rise far enough to permit the shoulder 157 to be engaged by the bail 158 so that the corresponding hammer will in such instance not be released by the bail. In order that all zeros to the right of a significant character shall be printed, however, means are provided for tripping the hammers of such type. These means comprise a lever 174 which is pivotally mounted on each hammer latch 152 and is adapted to engage a projection 175 on the next latch 152 to the right thereof, so that any latch 152 which is actuated by the bail 158 will in turn cause actuation of the latch 152 to its right. In order to split the zero control, the rear end 176 of lever 174 may be depressed to raise said lever out of co-operation with the adjacent hammer latches 152. In order to lock any one or more of the printing hammers against operation so as to permit the corresponding type bars to operate for accumulating purposes without printing, the following mecha-

nism may be provided. Loosely mounted on shaft 159, Fig. 6, are brackets 177 carrying a plate 178 and adapted to be actuated by a lever 179. Projections 180 (see also Figs. 6^a and 6^b) slidably mounted in plate 178 have ratchet latches 181 and may be raised and lowered by the operator into operative or inoperative positions. Normally these projections are in their lowered position. If it is desired to lock certain of the hammers against operation the corresponding projections 180 will be pushed upwardly and the plate 178 rocked to the dotted line position of Fig. 6 so that the projections 180 will rest under the levers 155 and when the pins 172 release such levers they will not be permitted to move into cooperation with bail 158 and the corresponding hammers will not be released by operation of said bail. Obviously the levers 174 connected with the particular hammers will be moved to inoperative position so that the hammers will not be released through this agency. In order to restore the hammers 148 after the printing operation, a bail 182 is provided. This bail is fixed on a shaft 149 which is adapted to be rocked by a link 183, (see Fig. 4) connected to a lever 184 fixed on a shaft 185 on which is also fixed the lever 186, having a link 187 connected thereto and reaching downwardly as seen in Fig. 4^a to a lever 188 fixed on a shaft 189 (see also Fig. 9). This shaft carries a lever 190 having a cam follower 191 cooperating with a cam 192. Spring 187^a, Fig. 4, holds the follower against the cam. Immediately after the operation of the hammers the cam 192 will operate to turn the shaft 149, Fig. 6, in a counter-clockwise direction to move the hammers into a latching cooperation with latch members 152.

Accumulator

Mounted on each type bar 73 is a rack member 193 having slideable connection as shown at 194, so that the racks may move up and down relatively to the bar, a distance equal to one tooth space. A spring 195 normally tends to hold the rack in its lower position with respect to the type bar. As seen in Fig. 13^a, an accumulator wheel 196 is adapted to mesh with the rack 193. This accumulator wheel may be provided with twenty teeth and may also have two carrying projections 197. These carrying projections are adapted to cooperate with a carrying latch 198 so that when the wheel reaches a zero position, turning in a counter-clockwise direction, as viewed in Figs. 13 and 13^a, the lever 198 will be pressed outwardly against the action of spring 198^a. This in turn will rock a latch member 199 loosely mounted on shaft 200 in a clockwise direction. This latch normally holds a carrying hook 201 which is loosely mounted on a shaft 202, in a relatively clockwise set position so that when the type bars

73 descend a lug 203 on the rack 193 will engage the hook 201 to latch up the rack 193 while the type bar 73 moves an additional tooth space to its normal position. When the latch 199 is rocked clockwise the spring 204 turns the hook member 201 out of the path of the lug 203, permitting the corresponding rack 193 to follow the type bar 73 an extra tooth space. The rack will thus roll into the gear 196 an additional value of one. It is, of course, understood that this additional "1" is rolled into the accumulator wheel of the machine next above the one which caused actuation of the member 198. Carrying hooks 201 are normally in the path of the lugs 203 and are restored to this position by a bail 205 fixed on shaft 206. Associated with each carrying hook 201 is a carry-suppression lock member 210, loosely mounted on a shaft 211 and having three arms 212, 213, and 214. This member is normally in the position shown in Fig. 6, with the arm 212 above a notch 215 in the carry hook 201. When the type bars 73 rise to the "9" position, the racks 193 will be carried just to the arm 214. But should the type bars rise beyond the "9" position the racks 193 will engage arm 214 and raise it, rocking member 210 so that arm 212 will be moved to the position shown in Figs. 13 and 13^a with respect to the notch 215. Thus, when the latch 199 releases the hook 201 as in Fig. 13, arm 212 will continue to hold said hook in position to stop the lug 203 to prevent carrying. The arm 213 of member 210 cooperates with a latching shutter 216 pivoted as at 217, Fig. 14, in the frame members 218, and pressed downwardly by a spring 219. When the member 210 is actuated by rack 193, it will thus be latched as in Figs. 13 and 13^a. A slotted guide plate 220 may be carried by the frame 218 to assist in holding the members 210 against lateral displacement. In Fig. 14, the shaft 206 is shown as having a lever 221 fixed thereon. This lever carries a flipper pawl 222, pivoted at 223 and pressed by a spring 224 against a pin 225. When the shaft 206 is rocked clockwise the flipper 222 will, by engaging the lateral projection 226, raise the shutter 216 to release the members 210, permitting the latter to be returned to normal position by their springs 227. When the shaft 206 is turned counter-clockwise the flipper will turn against the action of its spring and drag under the projection 226 without raising the latter, until it is free to spring into normal position. The accumulator wheels are loosely mounted on a shaft 230 carried by depending arms 231 (Fig. 12) loose on shaft 202. A link 232 is connected at one end to shaft 230 and at the other to a lever 233 fixed on shaft 234 (see also Fig. 12). The end of the shaft 234 is provided with a lever 235, (see Figs. 5 and 10) having a cam follower 236 adapted to cooperate with a cam 237. 130

Said cam is fixed on a shaft 238 on which is also fixed a double arm lever 259 having pins 240 and 241 respectively above and below the pivotal shaft 238. An actuating arm 242 having upper and lower notches 243, 244 is adapted to cooperate with either the upper pin 240 or the lower pin 241. The arm 242 is pivotally connected at 245 to a lever 246 fixed on a shaft 247. As shown in Fig. 4, shaft 247 has fixed thereto a lever 248 connected by a link 249 to a lever 250, Fig. 4^a, fixed on shaft 251. This shaft has a double lever arm 252 fixed thereto, which arm carries cam followers 253, 254, cooperating with complementary cams 255, 256, Fig. 8. At the end of a normal actuating cycle of the machine the accumulator wheels remain in mesh with the racks 193. At the beginning of a machine cycle the cams 255, 256 cause the shaft 247 to rock clockwise as viewed in Fig. 5. This removes the accumulator wheels from the racks 193 by raising cam 237 to rock shaft 234, pulling link 232, Fig. 12, to the right. After this has taken place the type bars begin to rise under control of the perforated card which is then being sensed. While the type bars are thus rising the shaft 206 is rocked clockwise as viewed in Figs. 13 and 13^a, the bail 205 engaging hook 201, to release the carry hooks 201 to locked relation with latches 199. Shaft 206 is actuated in the following manner. A lever 257 is fixed on shaft 206, Figs. 10, 14 and 4, and is connected by a link 258, normally held raised, to a lever 259, Fig. 4^a. This link is fixed on shaft 260 having a lever 261 fixed thereto, Fig. 9. The latter lever carries a cam follower 262 cooperating with a cam 263. About the time that the type bars start to descend, i. e., before any of the lugs 197 operate to unlatch the respective hooks 201, the shaft 206 is turned counter-clockwise to the position of Fig. 13^a so that the hooks 201 are free to be actuated by spring 204 to carrying position if released. At the end of the rising stroke of the type bars 73, the member 242, Fig. 5, is moved to the left, lowering cam 237, and the spring 264, Fig. 12, moves the accumulator wheels into mesh with their racks 193, so that on the descending stroke of the type bars a value corresponding to the position to which the type bars had risen will be rolled into the wheels. When the accumulator wheels are out of mesh with their racks they are adapted to cooperate with a projection 265 (Fig. 13) on a lever 266 to prevent accidental rotation.

Total taking

When a total is to be taken of a group of items which have been accumulated, the total clutch shown in Fig. 21 is brought into operation by the energization of magnet T. This energization is of very short duration being only long enough to release the mem-

bers 55, 57, so that the clutch will grip and cause the total shaft 48 to begin to rotate. After this shaft has rotated 180 degrees the shoulders 61^a and 64^a of members 55, 57 are caught by the latch member 63 unclutching the total shaft and stopping the same. This partial rotation of the total shaft shifts the member 242 from the upper position of Fig. 5 to the lower position shown in Fig. 15, so that its lower notch 244 will cooperate with the pin 241. This shifting is accomplished in the following manner. The link 267 connected to member 242 is connected at the lower end, Fig. 5^a, to a double arm lever 268 pivoted on shaft 269. This lever may have follower rollers 270, 271 cooperating with complementary cams 272, 273. When this shifting of member 242 takes place the parts being in the relative positions of Fig. 5, the cam edge 274 of member 242 engages pin 241 and forces the latter to the left raising the cam 237 to the position of Fig. 15. This, of course, de-meshes the accumulator wheels. After the total shaft 48 has turned its half revolution and stopped, leaving the parts in the positions of Fig. 15, the machine clutch M, Fig. 7, which was open during the operation of the total shaft, closes and causes the machine shaft 45 to operate again.

At the beginning of the machine cycle, as we have seen, member 242 is moved to the right. This will depress cam 237 and permit the accumulator wheels to mesh with their racks. Now, when the type bars rise, they will turn the accumulator wheels backward until the lugs 197 (Figs. 13 and 13^a) engage the upper edge of the hook end of lever 198. All of the wheels will thus be turned back to zero, and each type bar will have risen a distance corresponding to the number that stood in its respective accumulator wheel. With the type thus positioned, the hammers, Fig. 6, will be tripped in the usual manner and the data that stood in the accumulator will be printed.

The parts now return to normal as heretofore described in connection with the accumulating cycle.

At the completion of the machine cycle with the type bars restored to normal position the machine clutch opens and the total clutch once more comes into operation and causes the total shaft to turn the other 180 degrees back to its normal position. This moves the member 242, Figs. 5 and 15, back to its upper position in Fig. 5 and permits the accumulator wheels to again mesh with the racks. The total clutch is now open and the machine clutch closed and the machine is ready for further listing and accumulating operations. All of the timing and controlling of the operations which have been described are through cams and contacts which will be hereinafter more specifically described. At the end of a listing cycle of the machine the

5 accumulator racks 193, where carrying has taken place, will have descended one tooth space below their normal position so that before the type bars commence to rise under control of the accumulator wheels for totaling these racks must be restored this one tooth space. This must be done while the accumulator wheels are out of mesh with the racks. The following mechanism is employed 10 to accomplish this:

Below the accumulator racks is a bar 300, Figs. 6 and 12, slidably mounted in the frame member 301 for movement up and down. Lever arms 302 at the opposite ends of this 15 bar are adapted to raise and lower the bar. These arms are fixed on the shaft 303 on which is also fixed a lever 304 having pin and slot connection with a lever 305 fixed on a shaft 306. The latter shaft as seen in Fig. 20 5, which is a view taken from the opposite side of the machine, has fixed thereon a lever 307 connected by a link 308 to a lever 309, Fig. 5^a, fixed on a shaft 310 which in turn is provided with a lever 311 having a cam 25 follower 312 cooperating with a cam 313 on the total shaft 48. A spring 307 holds follower 312 on the cam. The cam 313 will in turning the 180 degrees, heretofore referred to, rock the shaft 310 clockwise, pulling 30 down upon link 308 and turning shaft 306 clockwise as viewed in Fig. 5, and counter-clockwise as viewed in Fig. 6. This raises the bar 300 and raises all of the racks 193 to their normal positions, to be latched by 35 members 201 (Fig. 13^a).

The cam 313 is shown as having on opposite sides two similar raised portions 314 and 315. These portions are provided to take up quickly any lost motion between the 40 arms 302 and the bar 300, and between the bar 300 and racks 193. Then after this lost motion has been taken up the cam commences slowly to raise the racks 193 and this is quickly accelerated until the parts reach 45 their positions with the follower 312 on the highest part of the cam 313 when the shaft 48 comes to rest. These parts remain in the positions described while the totaling is taking place and the bar 300 is again lowered to 50 its normal position, shown in Fig. 6, when the total shaft is turned its second 180 degrees back to normal.

Group indicating

55 In printing reports under control of perforated cards it is customary to use a certain field of the card comprising one or several columns of perforations to indicate a grouping to which the cards belong. A 60 group of cards relating to a particular commodity, for instance, will have punched in each card a number representing this commodity. The cards of such commodity are run through the machine in a single group, 65 followed by a group of cards representing some other commodity and therefore having a different designating number in the group designating field. The machine is adapted, when a change in this group number occurs, to suspend the feeding of cards through 70 the sensing portion of the machine, and after taking the reading from the last card of the group upon which the machine has been operating, to automatically control the subsequent operations of the machine. When 75 the first card of a group passes through a machine and is sensed and the data thereon run into the accumulator and printed upon the report sheet the machine is adapted to print with such data the group designation, 80 and to thereafter omit the printing of this designation during the rest of the accumulating operations relating to this group and to again print this designation on the total line when the totals are being printed. This 85 is accomplished in the following manner:

Referring to Fig. 10, carried in the accumulator frame 316 are several wheels 317. These wheels are somewhat similar to the accumulator wheels 196 and are carried on 90 the same shaft 230 therewith, but these wheels are not adapted to accumulate as they do not have the carrying connections common to accumulator wheels. The detail of these group accumulator control wheels 95 317 is shown in Fig. 12. The wheels are caused to mesh and demesh with the racks 193 whenever the accumulator wheels are so operated. Thus during an accumulating operation when the type bars rise under control of the number contained in the group 100 indicating field of the card and the wheels 317 are then meshed with the accumulator racks and the racks descend to normal position the group indicating number is rolled into these wheels. Thereafter the magnets 105 107, Fig. 6, associated with the type bars operating in connection with the group indicating field are rendered inoperative during the continuance of the accumulating operations upon the particular group of cards then 110 running through the machine. This is accomplished by the opening of certain contacts during the first accumulating cycle of the machine as will be more fully pointed out hereinafter. Now as the type bars 73 rise during each cycle of the machine the group indicating hole in the card will have 115 no effect upon the stop member 97, Fig. 6, so that the type bars associated therewith will rise to their uppermost limit. This will carry the last type member 74, which is the "9" type, above the printing position so that when the hammers 148 operate they will not strike any type and nothing will be printed 120 in the group indicating column on the report sheet. The type hammers will strike the bar 182 and will be restored along with the rest of the hammers that they may have 125 been tripped.

After the printing operation and the wheels 317 are brought into mesh with the racks 193 and the type bars then commence to descend the value of 10 will be rolled into the wheels so that when the parts are again in normal position these wheels will have turned 180 degrees and will be left with the same value therein that they had prior to the last operation. Each accumulating cycle of the machine will bring about this same result so that although the wheels 317 are constantly in operation the values contained therein do not change.

Now when the type bars rise during a totaling operation of the machine under control of the wheels 317 the stops 197 will cooperate with the member 198 in the same way that the stops 197 on the accumulator wheels do. The type bars will thus be stopped at positions corresponding to the value contained in the wheels 317 so that now when the hammers are tripped such number will be printed along with the totals. The wheels 317 are now in zero position and as the accumulator wheels and group indicating wheels are demeshed before the type bars descend the group indicating wheels will remain at zero ready for the next group of cards.

Paper line spacing

Referring to Figs. 4, 5 and 6, the report sheet is carried by the platen 76 mounted on a shaft 319 carried by the frame 320 of the paper carriage 321 in the usual manner. Fixed on one end of the shaft 319 is a ratchet wheel 322 adapted to be actuated by a pawl 323 carried by a lever 324 fixed on a shaft 325. When the shaft 325 is rocked counterclockwise as viewed in Fig. 4 the pawl 323 will engage the ratchet wheel and turn the latter one or two line spaces depending upon the position which the pawl takes with respect to the ratchet wheel. This position is in turn controlled through the pivoted lever 328 which has a cam portion to operate a link 327 and a handle portion through which the cam may be adjusted. The link 327 is pivoted to pawl 323 at one end and its other end is guided by a pin and slot connection of which the pin 326 is the pivot of lever 328. A spring 326 tends to pull the link 327 upwardly and hence adjust the pawl 323. A pin on link 327 cooperates with the cam on lever 328 so that as the handle of the lever is moved the link 327 assumes a position to correspond with the lever 328 in its lower position in Fig. 4. In this position the pawl will turn the paper one line space. If the lever 328 is raised to its upper position in cooperation with the notch 329 it will permit the pawl 323 to engage the ratchet wheel 322 at an earlier time in the stroke of the lever 324 so that the pawl will grip the wheel at an earlier time in its stroke and turn it through a greater angle or two line spaces.

Fixed to the shaft 325 is a lever 330 having a grooved wheel 331 cooperating with a bifurcated lever 332 spring pressed by a spring 333 as indicated in Fig. 6, and adapted to be adjusted by a set screw 334 to limit the clockwise movement of shaft 335. The lever 330 is fixed on a shaft 335 on which is also fixed a lever 336, Fig. 4, connected by a link 337 to a lever 338, Fig. 4^a, fixed on a shaft 339. The link 337 is normally held in its upper position by a spring 340. The shaft 339, Fig. 9, has fixed thereon a lever 341 carrying a cam follower 342 cooperating with a cam 343 on the machine shaft 45. Thus once during each listing stroke of the machine the shaft 339 and connecting parts will operate to turn the platen 76 one or more line spaces depending upon the position of the member 328. Means are also provided to cause the paper to be turned through an extra line spacing operation when a total is being taken so that the total line may be set off from the prior and succeeding groups. This is accomplished in the following manner:

The opposite end of shaft 335, Fig. 5, has fixed thereto a lever 344 adapted to be engaged by a pin 345 on a lever 346 on a stud 347. The rear end of lever 346 is connected by a link 348, normally held in its upper position by a spring 349, to a bell crank lever 350, Fig. 5^a, loose on the shaft 351 and having at one end a cam follower 352 cooperating with a cam 353 on the total shaft 48. This cam is adapted to actuate the lever 350 once during its first half revolution, which takes place when the total is printed, and once during the second half revolution, which takes place after the printing of the total. The operation of the parts causes the shaft 335 to turn counterclockwise as viewed in Fig. 5 or clockwise as viewed in Fig. 4 and will apply the extra stroke to the pawl 323 before and after the printing of the total. In order to permit the shaft 335 to be thus operated from the total shaft while the link 337 is idle the connection between the latter link and shaft 335 is by means of a slot 353'. Thus after the paper has been spaced by the operation of the machine shaft during the last accumulating cycle it is spaced once more by the total shaft at the beginning of the total cycle. Then at the completion of the printing of the total shaft spaces the paper once more before the machine shaft again comes into control.

Lateral adjustment of platen

The paper carriage 321, Figs. 4 and 6, is mounted on the frame portion 355 of the machine and is adapted to move laterally on the bearings 356, 357. The bolt 358 is adapted to secure the carriage in any position to which it may be moved. To set the carriage the nut 359 may be loosened so that the carriage may be moved with respect to its frame. A lever

365, Fig. 5, may then be depressed. This lever is fixed on a shaft 366 which in turn has fixed thereto a lever 367 reaching downwardly and adapted to cooperate with a notched bar 368 fixed to the frame member 355 of the machine. Depression of lever 365 will rock the lever 367 out of cooperation with the member 368 and will release the carriage for lateral movement. After the carriage has been moved to the desired lateral position the lever 365 may then be released permitting the lever 367 to engage the member 368 to hold the carriage to the position to which it has been adjusted. The nut 359 may then be secured to hold the carriage rigidly in this position.

Below the platen 76 are shown rollers 387 to hold the paper against the platen. In order to insert and adjust a new piece of paper the pressure of these rollers may be released by the actuation of a lever 388, Fig. 5. The movement of this lever in a counter-clockwise direction will move the cam 389 permitting the spring 390 to actuate the lever 391 which carries the rollers 387. The spring 390 also serves to hold the lever 392 with a roller 293 against the notched wheel 394 to prevent accidental rotation of the platen.

Ribbon feed and control

Referring to Figs. 2, 4, 5 and 6, the printing ribbon 369 is carried by the spools 370, 371 and passes around the guide spindles 372 and through guide members 373. The ribbon spools 370, 371 are fixed on shafts 374 and 375. These shafts carry bevel gears 376 adapted to be engaged by similar gears 377 on a shaft 378. The shaft 378, as shown in Fig. 6, has fixed thereon a ratchet wheel 379 adapted to be actuated by a pawl 380 when the hammer restoring member 182 operates. The guide members 373 are adapted to be engaged by a knot or the like near the end of the ribbon so that the feeding of the ribbon will move the members 373 to rock the shaft 374 unlatching a member 381 to cause lateral shifting of the shaft 378 to reverse the feeding of the ribbon. In order to shift the ribbon vertically to print in a different color the shafts 374 and 372 are adapted to be raised or lowered by bell crank levers 383, 384 which are linked together by a link 385. A lever 386 fixed with respect to one of the levers 384 may be provided to effect this shifting.

Spark contacts

Referring to Figs. 6 and 18, each stop 97 is engaged on a shoulder 400 by a bell crank lever 401 pivoted at 402. When the stop is in its normal position, the bell crank is in position to hold contacts 403 closed. As shown in Fig. 6, these contacts are arranged in two rows, one above the other, so that each alternate bell crank is associated with the upper row of contacts 403 and the intermediate bell

crank with the contacts 403 on the lower row. This arrangement is to condense the lateral spacing of the contacts. When the magnet 107 is energized to release the stop 97, it will thus be seen that the corresponding contacts 403 are immediately opened. These contacts are in series with the circuit through the magnet 107 and the brush which co-operates with the perforations in the card to energize the magnet so that the moment the circuit is completed and the magnet becomes energized, the circuit is broken through contacts 403 before the reading brush passes out of the hole in the card. In this way the slight sparking that may occur by the breaking of the circuit is taken by the contacts 403. This will prevent pitting at the brushes that co-operate with the perforations in the card. When the stop 97 is restored by the bail 125, as described, the bell crank 401 is also restored to its normal position, closing the contacts 403.

Group indicator contacts

Adjacent the contacts 403, as will be seen in Fig. 2, is a group of contacts 405 which are used for group controlling in a manner to be hereinafter described. Directly beneath the contacts 405, as seen in Fig. 17, is another group of contacts 406. All of the contacts 406 are closed by a bail 407 which is held in its upper position by a three arm lever 408 pivoted at 409 and locked in position by a pin 410 on a slide member 97^a, which is similar to the type bar stop 97, and operates in the same manner. A spring 100^a tends to pull the member 97^a to the left, as viewed in Fig. 17. Latch 101^a locks the member 97^a, to the right. A magnet G¹⁴ operates in the same manner as magnets 107 to actuate the latch 101^a to release the member 97^a, which, under the tension of its spring and also the tension of the leaves of the contacts 406 on the bail 407, causes the lever 408 to turn in a clockwise direction to permit the contacts 406 to open. A link 411, connected to one arm of lever 408, is also connected to a lever 412 fixed on a shaft 413. This shaft, Fig. 4^a, has a lever 414 fixed thereon, which lever is in turn connected by a link 415 to the lever 416 fixed on a shaft 440. The latter shaft, as seen in Fig. 9, has a lever 417 fixed thereon carrying a pin 418 adapted to be engaged once each revolution of shaft 45 by a cam lug 419 fixed on the side of the cam 343. The cam 419 acting upon pin 418 will actuate the latter slightly and cause a slight clockwise rotation of the lever 408, Fig. 17, so as to slightly reduce the spring pressure acting on the pin 410. This takes place just as the magnet G¹⁴ is about to be energized so that the latter will be able to actuate the latch 101^a. The pin 418 rides off the lug 419 while the magnet G¹⁴ is energized so that the latch 101^a, having been actuated, will now permit the member 97^a to move to the left to release all of the contacts 406, permitting the latter

to open. This in turn permits the pin 418 to move upward, as seen in Fig. 9, so that the lug 419 on the next and subsequent revolutions will pass on the outside of the pin without touching it. The contacts 406 will not be closed again until the total shaft 48 is brought into operation. This shaft carries a cam 420 (Fig. 5^a) having a hump 421 adapted to engage the follower 422 on a lever 423 fixed on shaft 424. This shaft also has a lever 425 fixed thereon, connected by a link 426 to a lever 428 fixed on the shaft 413. The link 426 is normally pulled downwardly by a spring 427 to hold the follower 422 in contact with its cam. When the cam raises link 426, it rotates the lever 408 counterclockwise, closing the contacts 406 and latching the member 97^a to the latch 101^a. Referring to Fig. 19, the latch 101^a is assisted in its return to normal locking position by the spring pressed lever 147 carried by one of the bars 134.

Group control contacts

Referring again to Fig. 17, above the group indicator contacts 406 is a group of control contacts, the purpose of which will be described in connection with the description of the wiring diagram. The manner in which the contacts operate is as follows:—A lever 401^a, similar to lever 401 in Fig. 6, is controlled in the same manner as the latter, having a stop similar to stop 97, which in turn is released by magnets 107. The stop which co-operates with the levers 401^a does not co-operate with any type bars because they are to one side of the latter, as will be seen in Fig. 2. In other respects the parts are the same as shown in Fig. 6 and are, therefore, not duplicated in the drawings. Each lever 401^a will be controlled by one column on the card and, when released, will permit the contacts 405 to open. At the same time a pair of contacts 405^a, which are normally open, will be closed by the depression of the spring blade 427 acting on the blade 428. The levers 401^a and associated parts are restored in the same manner as the levers 401.

Total setting contacts

At the right of the row of contacts as seen in Figs. 2 and 4, are three sets of contacts 430. Each of these sets comprises a pair of normally closed contacts 474 and a pair of normally open contacts 432. Turning to Fig. 17^a, a bail 433 holds the contacts in their normal positions. This bail includes a lever 408^a latched in position by a pin 410^a on a stop member 97^b co-operating with a latch member 101^b. A magnet TS³ is adapted to actuate the latch 101^b to release the contacts to permit contacts 474 to open and 432 to close. The lever 408^a is connected by a link 434 to a lever 435 fixed on a shaft 436. This shaft, Fig. 4^a, has fixed thereto a lever 437 connected by a link 438 to a lever 439 fixed on shaft 169. The

latter shaft has fixed thereon a lever 441 (Fig. 9) having a pin 442 adapted to be engaged once each revolution of the machine shaft 45 by the cam lug 419 to ease the spring strain so that the magnet TS³ can release the member 97^b to permit contacts 474 to open and 432 to close. The restoration of the parts is effected by the link 426, Figs. 5 and 5^a, connected to a lever 443 also fixed on shaft 436 in the same manner that the group indicator contact parts are restored. It is to be noted that the connection between the links 426 and the levers 428, Fig. 5, and 443, Fig. 5^a, are lost motion connections by means of pins and slots as seen at 444. The reason for this type of connection is to permit the operation of the cam lug 419 which turns the parts slightly as described to release spring tension.

Machine cam contacts

Referring to Fig. 7, the machine shaft 45 has fixed thereon a gear 445 meshing with a gear 445^a, which in turn meshes with a gear 446, Fig. 4^a, fixed on a shaft 447, which we will call the machine cam contact shaft. This shaft carries a number of cams, which we will call the M cams, and one of which, M¹, is shown in Fig. 4^a, co-operating with contacts M¹' to open the latter at a definite time in the rotation of the shaft 447. Referring to Fig. 16, all of the M cams are shown mounted on the shaft 447 co-operating with their individual contacts. In Fig. 27 the M cams are spread out and show their relationship to each other, and to what we may call their zero position represented by lines 448. The cams are shown in the positions which they occupy when the shaft 447 is in rotation. As the shaft begins to rotate, the several cams will successively pass through their zero positions, at which point they will release their contacts to permit the latter to close, or in some instances to open. Fig. 27 will serve as a sort of timing diagram for use in connection with the wiring diagram, hereinafter to be described, to show the times at which the contacts open or close.

Total cam contacts

In Figs. 7 and 5^a, the total shaft 48 is shown as having fixed thereon a gear 450 meshing with a gear 451, which in turn meshes with a gear 452 fixed on a total cam shaft 453. This shaft carries a number of cams, known as the T cams, one of which, T⁸, is shown in Fig. 5^a co-operating with contacts T⁸'. These cams and contacts operate in the same manner as the M cams and contacts. The cams are shown for timing purposes in Fig. 28, the zero line being shown at 454. The cams in this figure are shown in the positions which they occupy when the shaft is idle and indicate where in the cycle of the shaft 443 they close or open their respective contacts, which will be referred to in greater detail in connec-

tion with the wiring diagram. The total cam shaft, with its cams and contacts, is shown also in Fig. 16.

Control keys

Referring to Figs. 24, 25 and 26, the start, stop and total control keys are shown. The start key is shown as a double key designated ST. One of the shanks 455 of this key engages a lever 456 pivoted at 457 and acting upon a bail 458 to close several contacts designated F¹, F² and F³. The start key is normally held in the upper position by a spring 459. Depression of the start key closes the contacts F¹, F² and F³. These will be locked in this position by a latching lever 460 pivoted at 461 and actuated to latching position by a spring 462. The stop key is designated F and its shank 463 engages one arm of the lever system 460 and when depressed rocks said levers counter-clockwise, as viewed in Fig. 25, to unlatch the bail 458 permitting the contacts F¹, F² and F³ to open by their own resilience. The second shank 464 of the start key, Figs. 24 and 26, engages the upper leaf 465 of a pair of contacts ST¹ which are normally open. The leaf 465 has shank 466 adapted to depress a leaf 467 of a pair of contacts designated ST² which are normally closed. Thus, when the start key is depressed, the contacts ST¹ will close and contacts ST² will open. The total setting key is designated TS and is adapted to close the contacts TS¹, which are normally open. These contacts remain closed only while the total setting key is being held down manually. This is also true of contacts ST¹ and ST², which remain closed and open respectively only while the start key is being held depressed. The manner in which these contacts function in the control of the machine will, of course, be pointed out in greater detail in connection with the wiring diagram.

WIRING DIAGRAM

Starting the machine

Fig. 23 shows the wiring connections between the various magnets, contacts and control keys of the machine. In order to start the machine, the main switch 468 will be closed to supply current to the motor 3 to start the main drive shaft 10 of the machine. Presuming several groups of cards to be in the machine, the feeding of the cards and the sensing of the data contained thereon may be started in the following manner: The operator presses the start key ST closing contacts ST¹. This sets up a circuit as follows: from the positive side of the line 470 through wire 471 to a holding magnet H, contacts ST¹, wire 472, magnets C, contacts T⁴, wire 473, contacts F¹, contacts 474, wire 475, contacts M⁴ and back to the negative side of the line 476. The energization of the card feed clutch magnet

C releases the card feed clutch for operation and the feeding of the cards immediately commences. The operator then releases the start key, and the magnet H having been energized to close contacts H¹, holds the latter closed so as to continue the circuit through the magnets C by way of the wire 477. As the card feeds through the machine and depresses the members 37 and 38, the contacts 41 and 41' and 42 will be closed. A closing of contacts 42 will set up a circuit from the positive side of the line through magnet H, wires 477, 472, machine clutch magnets M, contacts 42, contacts F¹, contacts 474, wire 475, contacts M⁴ and back to the negative side of the line. The energization of the clutch magnets M will cause the machine shaft 45 to begin to rotate. This in turn causes the M cams to rotate to control their respective contacts; thus during each cycle of the cam shaft the cam M⁴B closes contacts M⁴B', after which the cam M⁴ opens contacts M⁴'. Then at a definite time in the cycle of the machine, cam M⁴B opens contacts M⁴B'. The circuit through the magnets C and M must now be diverted from the contacts M⁴' and M⁴B' to some other course. This takes place through wire 480, contacts 405* and wire 482, in the manner to be more specifically described in connection with group controlling. Should the cards fail to feed through the machine now, the card levers 37 and 38 will fail to be depressed and their contacts 41, 41' and 42 will open. The opening of the contacts 42 will open the circuit through the machine clutch magnet, so that the machine cam shaft will stop rotating. The stop, however, does not take place at the moment the contacts 42 open, because while the cam shaft is rotating, the contacts M²' and M²B' close for a portion of each cycle, and at a definite time during each cycle, both of these contacts are open so that when contacts 42 open, the machine will continue to operate until a definite point in the cycle, when the contacts M²' and M²B' will open and the parts are brought to a stop in a definite position. The machine may be stopped by the operator by depression of the stop key F. This opens contacts F¹ and at a definite time in the cycle of the machine contacts M⁵' and M⁵B' will both be opened and current will cease to flow through magnets M and C, so that both the machine clutch shaft and the card feeding mechanism will cease to operate. When the contacts F¹ are open, the current is shunted around said contacts through contacts 483 and contacts M⁵' and M⁵B'. The contacts 483 will be closed by the machine clutch magnet M and remain closed until said magnet becomes de-energized. The function of these contacts is as follows:—When cards fail to feed through the machine and the machine clutch opens, stop-

ping the machine cam shaft, the circuit is not broken through the card feed clutch and the feeding mechanism continues to operate. To stop the card feed then, the operator 5 may depress the stop key F to open contacts F¹. The contacts M⁵ being in their normal or closed position, would shunt the circuit around the contacts F¹ and fail to cause the stopping of the card feed unless there were 10 some other way of breaking the shunt circuit. Thus, when the machine cam shaft is idle, the contacts 483 will be open and there can be no shunt circuit around contacts F¹.

Listing and accumulating

25 Each socket of the group 484 of sockets is connected to one of the contact members 36, which is associated with one of the brushes 34 to co-operate with a different one of the 20 columns of hole positions on the card. If it is desired to accomplish listing and accumulating of the data contained in a specific column on the card, the socket 484 associated with that particular column will be connected 25 by means of a plug wire 485 to a socket 486. This plugging may be to any one of the several sockets 486 depending upon which type bar is desired to be controlled from the particular column on the card. Tracing the circuit through the plugging here illustrated, the following result will be effected. As the card is passing the brushes 34, the type elements will rise, synchronously passing the printing position. When a hole in the card 30 passes under the brush 34, a circuit will be established from the positive side of the line 470 to the common bar 487 through the appropriate one of contacts 403, magnet 107, plug socket 486, plug line 485, socket 484, contact 35 member 36, brush 34, common bar 488, wire 489, contacts T⁵, which are normally closed, contacts M⁵ or M'B⁵, which are closed during the time that a card is passing under the brushes 34 back to the negative side of the 40 line 476. The type bar will thus be stopped with the type element corresponding to the 45 position of the hole in the column on the card.

Group indicating

50 In this art the cards are usually grouped according to transactions or commodities or salesmen. In such case the cards of each group are given a special designation. This 55 designation usually takes the form of a number. This group number is registered in certain columns on the card. These particular columns may be so connected in the machine that the group designation will be printed on the report sheet when the first card of the 60 group is being sensed and the data therefrom is being printed and applied to the accumulators. The printing of the designation may thereafter be suppressed until the entire group has passed through the machine and 65 the total of the items taken from such group

is printed, at which time the group designation may again be printed to indicate the group to which the total belongs. This is effected in the following manner:—Referring to Fig. 23, a socket 484, associated with the contact block 36 and brush 34, which co-operates with the column containing the group designation, may be connected by a plug wire 490 to a socket 491 and a socket 492 may be connected by a wire 493 to one of the sockets 70 486, depending upon the position on the report that it is desired to print the group number. Now, when the hole in that column passes under the brush 34, a circuit will be established as follows: from the positive side 75 of the line 470 to the common bar 487, through contacts 403, magnet 107, plug socket 486, wire 493, plug socket 492, contact 406, plug socket 491, plug wire 490, socket 484, contact block 36, brush 34, common bar 488, wire 489, contacts T⁵, contacts M⁵ or M'B⁵, to the negative side of the line 476. The magnet 107 will thus control the positioning of the particular type bar to print the digit corresponding to the perforation in the card column. 80 During this card cycle of the machine the cam M¹ is adapted to close contacts M¹ after the last of the hole positions on the card has passed the reading brushes. This will complete a circuit through the magnet G¹⁴, providing the switch S⁵ has been closed for group indicating. The circuit is as follows: from the positive side of the line through contacts M¹, magnet G¹⁴, switch S⁵, contacts 85 42 and F¹, contacts 474, wire 475, contacts M⁴ to the negative side of the line. The energization of magnet G¹⁴ will release the restoring bail 407, as pointed out in connection with Fig. 17, so that the contacts 406 will open. Thereafter, as the rest of the cards of this 90 particular group pass through the machine, a circuit cannot be closed through magnets 107, by reason of the open contacts 406. Thus, there will be no further printing of the group number while the cards of this particular 95 group continue to pass through the machine, as the type bars will rise past the "9" position, or, in other words, they will rise corresponding to a value of 10 on the accumulator 100 wheels. The releasing of the hammer will, therefore, not strike any type element and the accumulator wheel will be turned 10 points, and rest containing the same value that it 105 contained before the type bar commenced to rise. When a total of the group is taken, the 110 wheels associated with the particular type bars will control the position to which said bar rises and the number rolled into the wheel under control of the first card of the group will be printed along with the printing of 115 the total for the group. During the totaling operation, the bail 407 closes contacts 406 ready for operation upon the next group of cards. Several of the columns on the card 120 may be employed for designating a group and 125 130

each of such columns may be connected through a set of contacts 406, magnet 107, to control printing on the report sheet.

Group control

- 5 The group indicating number may also be used to control the stopping or other operations of the machine, so that when the last card of a group passes through the machine, 10 the machine may be caused to stop or to take a total of the group. For this purpose a socket 494, corresponding with the column on the card containing the group designation digit, may be connected by a plug wire 495 15 to a plug socket 496. The plug socket 494, it will be seen, is connected through one of the wires 497 to one of the contact members 35 associated with brushes 33. Assuming that we are using but one column for group 20 controlling and that this column is the first on the card, a circuit is adapted to be established whenever connection is found through both of the cards at the same time. The card feeding is such that while one card is 25 passing under the brushes 34, the next succeeding card is passing under the brushes 33, and the timing of the card feed in both instances is such that as any hole position is passing under the brushes 34, the corresponding 30 hole position on the succeeding card will be passing under the corresponding brushes 33. Therefore, if the perforation in the two cards is the same, the brushes 33 and 34 will contact with elements 35 and 36 simultaneously. The circuit thus established is as follows:—from the positive side of the line 35 through wire 498, to common bar 499, the first of brushes 33, to the corresponding contact block 35 and wire 497 to the plug socket 494, 40 plug wire 495, socket 496, contact 405, magnet 107', plug socket 491, plug wire 490 (which is the same plug wire that is used for group indicating from this particular column) to socket 484, through the corresponding 45 one of wires 500 to contact block 36, and the first of the brushes 34, common bar 488, wire 489, contacts T', contacts M' and M'B', to the negative side of the line. This circuit energizes the magnet 107' and opens contact 50 to take the spark from the card reading brushes, which contacts, as we have seen, remain closed until the end of the card cycle. It is while these contacts are closed that the contacts M' and M'B' are both opened during 55 a short portion of the card cycle, so that the circuit through the machine clutch M and the card feed clutch C will pass from contacts 474 through wire 480, contacts 405^a, wire 482, contacts 41' and 41, if the card lever 37 is depressed by a card, to the negative side 60 of the line. In the diagram four sets of contacts 405^a are shown as being sufficient to illustrate the operation of the machine. If group indicating and group controlling is being effected through group designating num-

ber involving four digits, each of these sets of contacts will, of course, be employed, but if only three columns are being used, one of the sets of contacts 405 may be shunted out of the control circuit by connecting the plug wire 501 to plug socket 502. By this method of plugging any number of sets of contacts 405^a may thus be plugged out, leaving the machine to be controlled by the remaining contacts. The plugging of these contacts may be effected from either end, thus the wire 482 may be connected by a plug wire 503 to a plug socket 504 to shunt out the lowermost of the sets of contacts 504—similarly a greater number of contacts 405^a may be shunted out in this manner. If several of the columns on the card are plugged for group controlling, all of the sets of contacts 405 plugged into the circuit must, of course, be closed when the contacts M' and M'B' are opened in order 85 to permit the machine to continue a listing and accumulating operation. At any time that one of the digits in the group control column changes, the card containing such change will be in co-operation with the 90 brushes 33 while the last card of the previous group is in co-operation with brushes 34. Presuming the digit perforated in the card of the previous group to be "3" and the digit perforated in the card co-operating with 95 brushes 33 to be "4", the group control circuit will not be established since while the "3" perforation is passing under the brush 34 the "3" position which is not perforated is passing under the corresponding brush 33 100 and no contact is made by the latter brush with contact member 35. Thus, the corresponding set of contacts 405 will not be closed at this time, so that when contacts M' and M'B' open, the circuit cannot pass 105 through the wires 480 and 482 as has been pointed out. The circuit will, therefore, be through the magnet TS³, which so long as the non-resisting circuit existed passed around this magnet. This circuit passes 110 through the magnet, as stated, and through contacts 41 to the negative side of the line, and then energization of the magnet TS³ opens contacts 474 and closes contacts 432 115 as described in connection with Fig. 17^a. The opening of contacts 474 breaks the circuit through the machine clutch magnet M and card feed clutch magnet C and the machine cam shaft and the card feeding mechanism stop. If it is desired to operate the machine 120 without the automatic group control, the switch S⁴ may be closed so that a circuit through wires 480 and 482 cannot fail and the magnet TS³ will not be energized.

Manually initiated total setting

The machine may be set up so as to stop at the end of a group of cards, after which the operator can strike the total by the operation of manual control elements or the set up may 125

be such that the machine will automatically take the total at the end of a card group and then automatically resume registering operations upon the next group of cards. We will first describe the means for taking a total under manual control.

Presuming the machine to have stopped on a change in the group designating number, the totals of the data accumulated from the 10 group may be taken by first pressing the total key TS. This will close the following circuits from the positive side of the line through contacts ST², wire 505, total clutch magnet T, contacts TS¹, contact MC, which will be 15 closed by the machine clutch magnet when the latter is de-energized, contacts FC, closed by the feed clutch magnet when the latter is de-energized, contacts T¹', which are closed when the total shaft is in its normal position, 20 back to the negative side of the line. The consequent energization of the magnet T permits the total clutch to come into operation and the total clutch shaft will begin to rotate. As soon as this happens, the cam T¹ releases 25 contacts T¹', permitting the latter to open and break the circuit through the total clutch magnet T, so that the total clutch will be thrown out, as described, after turning 180 degrees, and the total cam shaft will stop in 30 this position. The machine is then ready for the taking of a total, which is now accomplished by pressing the start key ST to close contacts ST¹. The card feed clutch magnet will not be energized now because the total 35 shaft will turn cam T⁴ to open contacts T⁴', but the machine clutch magnet will be energized through the following circuit:—from the positive side of the line through wire 471, magnet H, contacts ST¹, magnet M, contacts 40 T³', which will have been closed by cam T³ on the total cam shaft to permit the current to flow in the event that contacts 42 are opened if there is no card over the card lever 38. The current then passes through wire 473, contacts 45 F¹, contacts 474, which will have been closed by the total cam shaft, wire 475, contacts M⁴', to the negative side of the line. The machine cam shaft will now rotate in the usual manner, but the accumulator wheels will mesh 50 with the racks before the type bars commence to ascend so that the type bars will now be controlled by the accumulator wheels according to the data contained in said wheels. The type will thus be stopped in positions to print 55 the data standing upon the accumulator wheels. The wheels will then be withdrawn, as we have seen, and the type bars will descend, leaving the wheels clear and at zero ready for a new accumulating operation. 60 When the totaling set-up is effected by the total shaft, a cam T⁶ will permit contacts T⁵' to open so that the usual listing and other circuits passing through the reading brushes cannot be closed to effect the operation of the 65 machine. During the 180 degree rotation of

the total cam shaft, the raising of the accumulator control racks 193 from their minus one or carrying position to their normal zero position is effected. While a total is being taken and the machine shaft is operating, the contacts M⁴' and M⁴B' will, in the usual manner, open the normal circuit through the machine clutch magnet, or, in other words, shunt the circuit around the total-setting magnet TS³. This, of course, takes place 70 after the total has been printed and the type bars have returned to their normal positions. The current will then flow through the magnet TS³ and again break the contacts 474, causing the machine cam shaft to stop rotating. The operator will then press the list setting key L, closing contacts L¹, completing a circuit through the total clutch magnet T as follows:—from the positive side of the line through contacts ST², wire 505, magnet 75 T, wire 506, contacts L¹, contacts T²' (which will have been closed by the first 180 degrees movement of the total cam shaft carrying cam T²), and to the negative side of the line. The total cam shaft will then commence to rotate and the cam T² will immediately permit contacts T²' to open, breaking the circuit through the magnet T so that the clutch will disengage after the shaft has turned 180 degrees back to the normal position. The machine will now be ready for a new listing and accumulating operation, which, of course, may be manually initiated, as has already been described.

Automatic totaling

100

To set up the machine to take its own total automatically when a change in the group designation number occurs, the operator will, before starting the machine, close switches S¹ and S². Now, when the change in group designations occurs and causes the energization of magnet TS³, breaking contacts 474 and closing contacts 432, the closure of contacts 432 will initiate the following 105 circuit: from the positive side of the line to contacts ST², wire 505, total magnet T, switch S¹, wire 508, contacts 432, contacts F³, which are normally closed, wire 509, contact M⁹', which are in closed position at 110 the moment that contacts 432 are closed, but are broken immediately by the cam M⁹ before the machine cam shaft stops rotating. The current then passes from contacts M⁹' through wire 510, contacts MC, contacts FC, 115 contacts T¹', to the negative side of the line. The magnet T being thus energized will initiate the rotation of the total cam shaft as in the former instance to set up the machine for totaling operation. Contacts T¹' will, as 120 pointed out, open as soon as the total shaft begins to turn so that the total shaft will stop after turning 180 degrees. The total shaft will, during this set-up operation, close contacts T²' by the cam T⁷ causing the fol- 125 130

lowing circuit:—from the positive side of the line through wire 471, magnet H, contacts T², switch S², contacts F², which are normally closed, wire 472, magnet M, contacts T³, contacts F¹, contacts 474, which, as we have seen, are again closed, wire 475, contacts M⁴, to the negative side of the line. The operation of the machine cam shaft will, in the usual manner, now take the total of the data standing in the accumulator wheels, at the end of which operation contacts 474 will be broken, causing the machine cam shaft to stop. Near the end of the operation of the machine cam shaft, the cam M⁶ closes contacts M⁶', setting up a circuit through the total magnet as follows:—from the positive side of the line through contacts ST², wire 505, magnet T, wire 506, contacts M⁶', contacts T²', which are now closed, wire 507, to the negative side of the line. The total magnet T now permits the total clutch to operate to turn the total shaft. Contacts T²' immediately open, so that the shaft will stop after rotating 180 degrees back to normal position.

Automatic resumption of listing and accumulating

If it is desired to cause the machine to automatically continue listing and accumulating of the items on the next group of cards after taking a total of the preceding group, the switch S³ is also closed by the operator before the machine is started. Near the end of the resetting half turn of the total shaft, the cam T⁸ closes and again opens contacts T⁸'. During the moment that these contacts are closed, a circuit is set up from the positive side of the line through magnet H, wire 511, contact T⁸', switch S³, contacts F², magnet C, contacts T⁴', which have been reclosed, wire 473, contacts F¹, contacts 474, wire 475, contacts M⁴' to the negative side of the line. The breaking of the contacts T⁸' does not open the circuit through the magnet C, as the holding magnet H will have caused contacts H¹ to permit the circuit through the magnet C to continue. If at this time the card lever 38 is depressed by a card, the circuit will, of course, also pass through the machine clutch magnet M and the machine cam shaft, as well as the card feeding mechanism, will commence to operate.

Zero stops

In order that all of the type bars which may not be needed in connection with certain report cards shall not rise while the machine is operating upon such cards, these type bars may be so controlled as to stop at their zero positions. For this purpose, all of the plug sockets 486 are connected by resilient contact members 514 to the common bar 515. The spring contact 514 is adapted to be disengaged from the sockets

by the plug connections 485 and 493 whenever these plugs are inserted, so as to break the electric connection with bar 515. All sockets 486 then that are not so plugged will remain connected to the common bar 515. Thus, as the machine commences a listing and accumulating cycle, a circuit is completed through the respective magnets 107 as follows:—from the positive side of the line to the common bar 487, contacts 403, magnet 107, plug socket 486, contact 514, bar 515, wire 516, contacts M³', which are closed at the beginning of the machine shaft cycle by cam M³, wire 517, contacts M⁷', which close the moment the machine cam shaft commences its cycle to the negative side of the line. This will release the respective type bar stops 97 to stop the type bars at their zero positions.

Carrier columns

In accumulating from a given number of columns on a card, say from five columns, these five columns are connected, of course, to five type bars and accumulator wheels. It is necessary then to provide an extra accumulator wheel and type bar for carrying, if the number being accumulated is to be a large one. These extra wheels and type bars may be brought into co-operation with the aforesaid five wheels and type bars by plugging in the following manner:—a plug line 518 is inserted in plug socket 486 and the socket 519, the latter being in the common bar 520. The magnet 107 thus connected is, of course, the one to the left of the first accumulator wheel of those being used to accumulate the data in question. During normal accumulating operations, a circuit will be established as follows:—from the positive side of the line through the magnet 107 in question, plug socket 486, wire 518, socket 519, bar 520, wire 521, contacts M⁸', which are closed at the beginning of the listing cycle of the machine cam shaft, through wire 522, contacts T⁵', which are normally closed, wire 517, contacts M⁷', which are closed at the beginning of the machine cycle, to the negative side of the line. This causes the carry type bar to stop at zero position during the listing operations, so that this type bar does not operate its accumulator wheel, but if the wheel to the right passes to its zero, it will in the usual manner add one to the carry wheel. Now, when a total is being taken, the first or setting up half cycle of the total shaft will open contacts T⁵' so that when the type bars rise to take a total, the circuit cannot be closed through the magnet 107 associated with the carrying type bar. Thus, the said type bar is free to rise under control of the accumulator wheel and will print the value which has been carried to this wheel. Any number of bars may be connected in this manner for carrying purposes. If a wheel

which has been connected for carrying purposes in this manner is not actuated by the carrying mechanism during accumulating operations, it will, of course, stand at zero when the totaling operation takes place. In this case, the type bar controlled by such wheel will be stopped at once and no printing will be effected from this bar since zeros are printed only when there is a significant character to the left thereof.

10 *Make and break contacts*

Several of the contacts in the diagram are shown double, as for instance, the contacts M²' and M²B', which are operated by cams M² and M²B respectively and serve to close the same circuit. The reason for this double arrangement is to effect a sharp making and breaking of the contacts, or, in other words, to make the contact at a precise point in the cycle of the machine and to break at a precise point. Thus, it will be seen that with the contacts M²' and M²B' open while the machine shaft is idle, the circuit across these contacts will be closed at a definite time in the cycle of the machine when the cam M² releases its contact. While these contacts are thus closed, the cam M²B will gradually close contacts M²B', after which cam M² opens contacts M²', but the circuit continues to be closed. Then at a definite time in the cycle of the machine, cam M²B releases the contacts M²B' to open. The other double sets of contacts shown in the diagram operate in the same manner to either make or break the circuit.

35 *Miscellaneous contacts*

In series with the contacts M⁵' and M⁵B', which are adapted to shunt the current around the stop switch contacts F¹, is shown a pair of contacts 483. These contacts are normally opened, and are closed by the machine clutch magnet when the latter is energized, or, in other words, when the machine cam shaft is rotating. When the said shaft is idle, these contacts are open so that if the machine shaft is idle while the card feed mechanism is operating, the operator may stop said mechanism by depressing the stop key, otherwise depression of the stop key would not open the circuit through the magnet C, as the contacts M⁵' would be closed and the card feed mechanism would continue to operate.

55 The contacts F³ in the automatic total circuit are normally closed, and are opened when the stop key F is depressed. This is to permit the operator to stop the machine should he depress the key at the moment that the machine is going in to an automatic total operation. In other words, should the operator press the key while the magnet TS³ is opening contacts 474, and closing contacts 432, the automatic total circuit through contacts 432 would be closed and the machine

would continue to take such total instead of stopping.

The contacts F² are also normally closed and are opened by depression of the stop key. The function of these contacts is to permit the operator to stop the machine from resuming a listing and accumulating operation after completing an automatic totaling operation when the machine had been set up for such resumption. This may be done by pressing the stop key at the completion of the totaling operation to open the circuit at F². The circuit being thus broken through the holding magnet H, the latter will permit contacts H¹ to open so that when the operator again releases the stop key, the machine will remain at rest.

The contacts ST² are normally closed, but are opened when the start key is depressed to start the operation of the card feeding mechanism and the machine cam shaft. As seen in Fig. 26, the contacts ST² will be opened by the peg 466 before the contacts ST¹ close; thus should the total circuit be closed by accidental closing of contacts #TS¹, such circuit would be opened by the start key before the other parts of the machine commence to operate. This will prevent the machine from starting to operate for listing and totaling at the same time.

The contacts 403 and 405, as we have seen, are open by energization of the magnets 107 and 107' respectively, the moment a contact is made by the card reading brushes through a hole in the card. Thus, the circuit through the card reading brushes is broken before the brush rides out of the perforation in the card and the slight sparking, if any, takes place at contacts 403 and 405 instead of at the brushes.

105 *List setting key*

A set of contacts L¹ is shown in the diagram. These contacts are normally open and may be closed by actuating the button L. The object of these contacts is to permit the operator to reset the machine for listing and accumulating in the event that he has already depressed the total setting key and caused the machine to be set up for totaling with the total shaft resting at a $\frac{1}{2}$ revolution. The closing of the contacts L¹ will complete a circuit from the positive side of the line through the total clutch magnet T, contact L¹, contacts T²', which under such condition would be closed, to the negative side of the line. Thus, the magnet T will again become energized and will turn its second half revolution to its normal position. At the beginning of this operation the cam T² will open contacts T²', so that although the operator may not release the key L in time to permit the parts to stop, the operation of contacts T²' will effect this result.

Last card switch

In the diagram there is illustrated a switch S⁶. The purpose of this switch is to cause the machine to be able to take its automatic total, when set up for this purpose, after the last card of the last group in the machine has passed the card lever 37, permitting contacts 41 and 41' to open. Normally when the last card passes card lever 37, it will be seen that current can neither go through the group control contacts 405^a nor through the total setting magnet TS³, because contacts 41 are open. But by turning the switch S⁶ to its dotted line position before starting the machine a circuit will be closed through the magnet TS³ when contacts M⁴ and M⁴B' are open, and the current passing through contacts 474 will continue through magnet TS³ and by way of the switch S⁶ to the negative side of the line. This magnet will then operate in its usual manner to close the contacts 432 causing the machine to take a total.

When the last card passes card lever 37 there is no card under brushes 33, and all of these brushes will engage contact members 35. Then, as the last card passes under brushes 34, and contact is made by certain of the brushes 34 with members 36 through the group designation perforations, circuits will be established through these brushes and the corresponding ones of brushes 33. This will cause closure of contacts 405^a, but as the card lever contacts 41' are now open the shunt circuit which would otherwise be established around magnet TS³ through contacts 405^a when contacts M⁴ and M⁴B' open is prevented. This prevents interference with the energization of magnet TS³ for the last card total.

Listing and tabulating speeds

In machines of this character it is sometimes desired to cause the machine to operate more slowly when taking a total than when listing and accumulating. This may be effected in the present machine in the following manner: The operating motor 469 as shown in the wiring diagram, Fig. 23, is disclosed as the shunt wound type. In addition to this, one of the leads 525 to the commutator of the motor is shown as including a resistance 526 and a contact T⁹ in parallel, the contact being normally closed to shunt out the resistance 526. A cam T⁹ mounted on the total cam shaft is adapted when the said cam shaft is turned through its first 180 degrees to totalling position, to open the contacts T⁹ so that the current to the commutator must now pass through the resistance 526, to cause the motor to operate at a slower speed. When the total shaft returns to normal position, contacts T⁹ will be closed again to permit the motor to resume its normal speed.

Having described my invention, what I

claim and desire to secure by Letters Patent is:

1. In an accounting machine, accumulator racks, accumulator wheels adapted to be actuated by said racks, carrying mechanism associated with said wheels and adapted when a wheel reaches its zero position to carry into the wheel of the next higher order, and means controlled by predetermined movement of an accumulator rack for rendering inoperative the carrying mechanism controlled by the corresponding accumulator wheel. 70

2. In a machine of the class described having type bars and type carried by said bars, accumulator racks also carried by said bars, accumulator wheels adapted to be actuated by said racks, means associated with said wheels for causing carrying from a wheel to the wheel of the next higher order and means for suppressing the effectiveness of said carrying means, said last named means being controlled by the extent of movement of said type bars. 80

3. In a machine of the class described, a printing device having gear teeth associated therewith, a gear adapted to mesh with said teeth to be actuated by said device, card-controlled means for controlling the operation of said device and means for causing a predetermined uniform operation of said device 90 after an initial operation thereof, said gear being adapted to control a subsequent operation of said device. 95

4. In a machine of the class described, a type carrier card-controlled means for controlling positioning of said carrier, a member adapted to be positioned by said carrier, means for suppressing the card-control of the operations of said carrier after an initial operation and means controlled by a change in a 100 characteristic reading in successive cards for causing said member to control the operation of said carrier. 105

5. In an accumulating device, an accumulating element adapted normally to be actuated to units of value from zero to nine, means for actuating said element, means controlled by said element when it passes through a predetermined point for causing a carrying operation and means operative when said actuating means moves said element, in one operation, to a value greater than nine for suppressing operation of said carrying means. 110 115

6. In an accounting machine a plurality of accumulator wheels, means for turning said wheels to positions of varying values, means operative when a wheel is turned to a predetermined position for carrying into the wheel of the next higher order, and means operative when a wheel is turned through more than a predetermined number of said positions for causing suppression of the carrying to the wheel of the next higher order. 120 125

7. In an accounting machine, a plurality of accumulator wheels, a rack for actuating each 130

wheel, carrying means controlled by said wheels, and means operative when a rack actuates a wheel through more than a predetermined value for suppressing operation of the carrying means controlled by that wheel.

5. 8. In an accounting machine, a group of accumulator wheels, a carrying lever controlled by each of said wheels, a normally in-

10 operative latch for each of said levers, and means operative when a wheel is turned through more than a predetermined angle for causing the corresponding latch to move to operative position to lock the corresponding lever out of carrying position.

15. 9. In an accounting machine, a plurality of accumulator wheels, means normally operative when a wheel passes its "9" position for carrying "1" to the wheel of the next higher order, and means operative when a value of "10" is added to a wheel in one operation for suppressing carrying to the wheel of the next higher order.

20. 10. In an accounting machine, a type bar having a plurality of type elements, an ac- 25 cumulator operated by movement of said bar, carry mechanism associated with said accumulator, and means operative when said bar moves beyond a predetermined position for causing a suppression of operation of the 30 carry mechanism.

35. 11. In a machine of the class described, a type bar having a plurality of type elements, an accumulator actuated by said bar, means controlled by movement of said bar for effect- 40 ing a printing operation, said bar being adapted in response to movement beyond a predetermined position to cause suppression of printing and accumulating.

45. 12. In an accounting machine, accumu- 46 lator wheels, means operative when a wheel is turned through a predetermined point for causing actuation of another wheel, and means operative when a wheel is turned through said point through a predetermined angle in a single operation for suppressing such actuation of such other wheel.

50. 13. In a tabulating machine, listing mecha- 55 nism, totaling mechanism, a common motor for operating said mechanisms, and automatically controlled means for causing a change of speed of said motor for each of said mechanisms.

55. 14. In a tabulating machine, listing mecha- 56 nism, totaling mechanism, a motor, means for interchangeably causing said motor to actuate said mechanisms, and automatic control means for causing a change of speed of said motor when changing from the actuation of one of said mechanisms to the actuation of the 60 other.

65. 15. In a machine of the class described, ac- 66 cumulating mechanism, totaling mechanism, means including separate electric connections for causing operation of said mechanisms, means for breaking one of said connections

for causing stoppage of its mechanism, means for causing the machine to change from the operation of one of said mechanisms to the operation of the other, said breaking means being adapted to break the other of said connections if actuated when said change is being made for causing stoppage of the other of said mechanisms.

70. 16. In a tabulating machine, an accumula- 75 tor with carry mechanism, a plurality of type carriers operatively connected with said accumulator, means for rendering one of said carriers inoperative while said accumulator is accumulating to permit carrying operations only in connection with its associated ac- 80 cumulating mechanism, means for controlling the carriers by said accumulator for taking a total, and means for rendering said inoperative carrier operative when taking a total.

85. 17. In a tabulating machine adapted to ac- 90 cumulate and to total, a plurality of accumula- 95 tor wheels, means including a type carrier for actuating said wheels, carrying connections between said wheels, card-controlled means for actuating the carriers, means for suppressing operation of one of said type carriers during accumulating operations of the machine to permit carrying operations only to the associated accumulator wheel, and means for releasing said one of said carriers during totaling operation of the machine whereby the said one of said carriers is controlled by its associated accumulator wheel.

100. 18. In a card-controlled machine, means controlled by record cards for controlling listing of items, total-taking mechanism, a common driving element, and means for oper- 105 atively connecting said driving element to either said listing means or said total-taking mechanism.

110. 19. In a machine of the class described, list- 115 ing means, totaling means, a common driving element, means for separately clutching said listing and totaling means to said driving element, and card-controlled means for actuating said clutching means.

120. 20. In a machine of the class described, ac- 125 cumulating means and control mechanism therefor, total-taking mechanism associated with said accumulating mechanism, a common driving element, means for separately connecting said accumulating and totaling mechanisms to said element for operating said mechanisms, and card-controlled means for actuating said connecting means.

125. 21. In a machine of the class described, means for accumulating, means for totaling, and a plurality of control cams adapted when in one position to cause the machine to per- 130 form accumulating operations and when in another position to cause the machine to perform totaling operations and means for selecting the several cam positions.

130. 22. In an accounting machine a plurality

- of accumulating elements, carrying mechanism associated therewith to carry to an element of an adjacent denominational order when an element moves a predetermined distance as a result of successive accumulating operations and means for suppressing the operation of the carrying mechanism when the element moves the predetermined distance as a result of a single entering operation. 5 70
23. In an accounting machine a plurality of accumulating elements, carrying mechanism associated therewith to carry to an element of an adjacent denominational order when an element passes a predetermined position and means for suppressing the operation of the carrying mechanism when the element moves from its normal home position to said predetermined position in a single uninterrupted movement. 10 75
24. In a machine of the class described accumulating control mechanism and totaling control mechanism, a movable actuator with means for moving the same differentially during an initial accumulating cycle and for 20 80
- 25 moving the same a predetermined distance during subsequent accumulating cycles, an entry receiving element operated by said actuator during each of its movements and means for differentially limiting the movement of 25 85
- 30 the actuator to conform to its differential movement during the initial accumulating cycle on a total taking operation. 90
25. In a machine of the class described, accumulating control mechanism and totaling control mechanism, a type carrier with 35 95
- means for moving the same differentially during an initial accumulating cycle and for moving the same a predetermined distance during subsequent accumulating cycles, 100
- 10 an entry receiving element operated by said carrier during each accumulating cycle and means including the entry receiving element for differentially limiting the movement of the type carrier on a total taking operation 105
- 45 to conform to its differential movement during the initial accumulating cycle. 110
26. In a machine of the class described accumulating control mechanism and totaling control mechanism, a reciprocable type 50 115
- 50 carrier and an entry receiving element with means controlled by the accumulating and totaling control mechanisms for operatively connecting the same to the type carrier at opposite ends of its stroke during accumulating 55 120
- 55 and total taking operations and means for moving the type carrier differentially during an initial accumulating cycle and for moving the same a uniform predetermined distance during subsequent accumulating 60 125
- 60 cycles to set the entry receiving element in the same position at the end of each accumulating cycle whereby it may control the position of the type carrier during a total taking cycle according to its setting during the initial accumulating cycle. 65 130
27. In a machine of the class described an entry receiving element, card controlled means for effecting entries thereon, means for suppressing the operation of the card controlled means after an initial entry and means for effecting a complete cycle of operation of the entry receiving element during each card cycle after its initial operation to ultimately retain the initial entry after each card cycle. 70
28. In a machine of the class described, a plurality of entry receiving elements, and entry control mechanism therefor normally disconnected therefrom, means for normally preventing operation of said entry receiving elements and means for selectively connecting said elements individually to said control mechanism for control thereby said means including devices for incapacitating the means for preventing operation of the entry receiving elements whereby the elements and only the elements selected for control by the control mechanism may operate. 75
29. In a tabulating machine, a plurality of type carriers, a plurality of corresponding accumulator elements with transfer devices between them and operating mechanism for said elements comprising a rack on each type carrier for operating the corresponding accumulator element, means for driving said type carriers to coincidentally move them to different printing positions and drive their corresponding accumulator elements, control mechanism and means for selectively associating the type carriers individually therewith, means controlled by the selective means to suppress operation of a type carrier not selected for control while permitting the transfer mechanism to operate and means for calling the suppressed type bar into operation during totaling. 80
- In testimony whereof I hereto affix my signature.
- JOHN ROYDEN PEIRCE.
